UNITED STATES PATENT OFFICE.

DAVID MCNAIR, OF BOSTON, MASSACHUSETTS, ASSIGNOR TO THE ROXBURY CARPET COMPANY, OF SAME PLACE.

DESIGN FOR A CARPET.

SPECIFICATION forming part of Design No. 12,325, dated June 21, 1881.

Application filed May 3, 1881. Term of patent 3½ years.

To all whom it may concern:

Be it known that I, DAVID MCNAIR, of Boston, in the county of Suffolk and State of Massachusetts, have invented a certain new and original Design for Carpets, of which the following is a specification.

This design is fully shown in the accompanying photographic illustration, forming part of this specification.

10 The design is composed of a ground or body having regular geometric ornamentation thereon, the detached irregular figures A, B, C, and D, resembling lattice-work, and the vine-like ornamentation having leaves and flowers thereon intertwined with the lattice-work figures 15 and arranged upon the ground, as shown.

I claim—

The design for a carpet, substantially as shown and described.

In testimony whereof I have signed my name 20 to this specification, in the presence of two subscribing witnesses, this 28th day of April, A. D. 1881.

DAVID MCNAIR.
